CLAIM

We claim the ornamental design for a shoe, as shown and described.

DESCRIPTION

FIG. 1 is a front, bottom perspective view of a shoe, showing our new design;

FIG. 2 is a rear, bottom perspective view thereof; and,

FIG. 3 is a bottom view thereof.

The dot-dash broken lines adjacent to the shaded area represent unclaimed boundaries of the claimed design. The broken lines depicting the remainder of the shoe show features that form no part of the claimed design.
